DESIGN FOR A POURING AND CLOSING LID FOR LIQUID RECEPTACLES

Willie O. Besaw, Fresno, Calif.

Application May 10, 1939, Serial No. 84,915

Term of patent 14 years

To all whom it may concern:

Be it known that I, Willie O. Besaw, a citizen of the United States, residing at Fresno, in the county of Fresno, and State of California, have invented a new, original, and ornamental Design for a Pouring and Closing Lid for Liquid Receptacles, of which the following is a specification, reference being had to the accompanying drawing, forming part thereof.

Figure 1 is a top plan view of the pouring and closing lid for liquid receptacles showing my new design with the valve in closed position.

Figure 2 is a similar view showing the valve plate in an open position.

Figure 3 is a side elevational view.

Figure 4 is a similar view taken at right angles to that of Figure 3.

I claim:

The ornamental design for a pouring and closing lid for liquid receptacles, as shown.

WILLIE O. BESAW.
